Josef Schulz.

UNITED STATES PATENT OFFICE.

JOSEF SCHULZ, OF BARMEN, GERMANY.

SHEET-METAL CASING FOR PHOTOGRAPHIC FILMS.

Application filed April 15, 1926, Serial No. 102,243, and in Germany February 2, 1926.

My invention relates to a multipartite sheet-metal casing for photographic films, more especially so-called film packs, and the characteristic feature of this casing, in contradistinction to the known film packs of sheet-metal, resides therein that it comprises only three sheet-metal members, viz, a box-shaped back member, a mid-member, and a closing cap holding said other two members together light-proof when it is in its closing position. Each of said three members consists of only one piece which is provided with such additional members as are necessary to connect the main members and to prevent them from being shifted relatively to each other.

The invention is illustrated diagrammatically and by way of example in the accompanying drawings, in which Figure 1 is a front-view of the improved sheet-metal casing for photographic films; Figure 2 is a plan thereof, Figure 3 a vertical section therethrough, and Figure 4 shows the top portion of Fig. 3, drawn to an enlarged scale.

On the drawing, 4 denotes the box-shaped back member, 5 the mid-member, and 6 the closing member or cap, each of which is punched or pressed of one piece of sheet-metal. The mid-member is provided at its upper rim with eyes 8 bent outwardly to the rear surface thereof, and the inner surface of the box 4 is provided with hooks 7, engaging the eyes 8 when the box is in its closing position, whereby the mid-member is held fast securely without preventing it from being movable in the necessary manner in the composed pack. To the upper rim of the inner side of the box member 4 a strip 9 of plush is attached, and a corresponding plush strip 10 is attached to the closing cap 6, the two strips being fastened by being pressed in. When the cap is in its closing position, the upper rims of the two plush strips lie flush and light-proof with respect to the paper flaps of the films inserted into the casing. The piece of sheet-metal pressed out of the cap and serving for holding fast the plush strip 10 forms also an abutment member 11 which, bears upon the web of the eye 8, as shown in Fig. 3, whereby the width of the gap between the upper and the lower edge or rim of the mid-member and the opposite portions is determined and this

member is securely prevented from getting disengaged from the hooks 7 when the cap is in its proper position on the casing.

There may be provided, however, abutment lugs 12 also on the opposite side of the cap 6, the purpose of these lugs being then also to secure the mid-member in its proper position with respect to the casing.

The mid-member 5 is provided, furthermore, firstly with the known springs 13 pressing, in connection with the known paste-board pressing flap (not shown), upon the non-exposed films, secondly, with cutting-outs of any desired shape, the purpose of which is to reduce the weight of the implement. The lower rim of the mid-member 5 is bent round tubularly, as at 14, Fig. 3, and this tubular portion and a bent insertion 15 of paste-board or the like form together a guide-way for the film when being pulled through from one side of the casing to the other side, and protect the respective film from damage.

It is obvious that the new constructional form of the casing is greatly simplified relatively to the known film-packs, concerning not only the finished case, but also the manufacture of the same. There are by far less pieces, less manufacturing phases, and simpler tools can be used. It is also evident that assembling the parts forming the casing, taking this latter to pieces, if required, filling the finished casing, and the like, can be effected without any bending of sheet-metal hooks or sheet-metal pivots or other connecting or closing means, also without the use of an adhesive and without cutting work, whereby the further advantage is attained that the casing can be filled with new film-strips as often as desired and can be used over and over again which is impossible with the known casings. Single or individual films which have already been exposed can be removed from the casing simply by disengaging the mid-member from the hooks 7, the hook-and-eye connection serving then at the same time as an abutment for the exposed films conveyed from one side of the casing to the other side thereof, so that the exposed films are prevented from being drawn beyond the abutment place.

The new constructional form of the film casing as described and shown by way of

example can be used in connection with films of any size, the advantages stated being attained in every case.

I claim:

- 5 1. A multipartite sheet-metal casing for photographic films and film-packs, comprising, in combination, a back-member (4), a mid-member (5), and a closing cap (6), said three parts constituting the film casing 10 proper, substantially as set forth.
2. A multipartite sheet-metal casing for photographic films and film-packs, comprising, in combination, a back member (4), a mid-member (5), a closing cap (6), and an 15 easily disconnectible hook-and-eye connection (7, 8) for said back member and said mid-member, said connection being adapted to serve also as a safety means against downward shifting of the said mid-member, substantially as set forth.
3. A multipartite sheet-metal casing for photographic films and film-packs, comprising, in combination, a back member (4), a mid-member (5), a closing cap (6), and 20 light-proof tightening strips (9, 10) of a soft material attached on one side to the sheet-metal portions connecting said back member 25

and said mid-member, and on the other side to that sheet-metal portion of the cap by which this latter is supported, substantially 30 as described.

4. A multipartite sheet-metal casing for photographic films and film-packs, comprising, in combination, a back member (4), a mid-member (5), a closing cap (6), and an 35 abutment lug (11) carried by said cap, and bearing upon said mid-member, and said lug being adapted to prevent this latter from being shifted upwardly, substantially as set forth. 40

5. A multipartite sheet-metal casing for photographic films and film-packs, comprising, in combination, a back member (4), a mid-member (5), and a closing cap (6), the lower rim of said mid-member being so bent 45 as to form the known tubular guide member (14) separated from the bottom of the casing by a conveying gap, and a curved guide member (15) inserted into said gap and being held fast therein by pressure, substantially as set forth. 50

In witness whereof I have hereunto set my hand.

JOSEF SCHULZ.
